(57) **CLAIM**

The ornamental design for a helmet illumination device, as shown and described.

DESCRIPTION

FIG. 1 is an isometric view of the design;

FIG. 2 is a rear view of the design;

FIG. 3 is a left side view of the design;

FIG. 4 is a front side view of the design;

FIG. 5 is a top view of the design;

FIG. 6 is a bottom view of the design;

FIG. 7 is an isometric view of the design in connection with a helmet;

FIG. 8 is a rear view of the design of FIG. 7;

FIG. 9 is a right side view of the design of FIG. 7;

FIG. 10 is a front view of the design of FIG. 7;

FIG. 11 is a top side view of the design of FIG. 7; and,

FIG. 12 is a bottom view of the design of FIG. 7.

The broken lines in the drawings illustrate the environment of use of the claimed design, but form no part of the claimed design.
